UNITED STATES PATENT OFFICE.

ROBERT S. MENNIE, OF CHICAGO, ILLINOIS.

FLEXIBLE STAY-BOLT CONSTRUCTION.

Application filed August 4, 1919. Serial No. 315,178.

To all whom it may concern:

Be it known that I, ROBERT S. MENNIE, a subject of the King of Great Britain, residing at Chicago, in the county of Cook and 5 State of Illinois, have invented certain new and useful Improvements in Flexible Stay-Bolt Constructions, of which the following is a specification.

My invention relates to improvements in 10 staybolts, such as are used, for example, in locomotive boilers.

In such boilers there is a certain relative movement between the wall of the fire box and the boiler wall, these walls being known 15 as the inner and outer sheets respectively. Said walls are not only held at a fixed distance from each other by the staybolts against the steam pressure which tends to force them apart, but said staybolts must 20 also permit this slight relative movement without substantial leakage of steam. To meet these requirements, so-called flexible staybolts have been used heretofore, the outer ends of which were enlarged to cooperate 25 with a sleeve, forming in effect a ball and socket joint, thereby permitting the necessary freedom of movement at that end of the staybolt.

One of the objects of the present invention 30 is to provide an improved staybolt connection which is in fact flexible, i. e., means being provided whereby relative movement of each end of the staybolt is permitted with reference to the adjacent sheet. An- 35 other object is to provide a flexible staybolt of this character so devised as to permit the steam to blow outwardly when the staybolt breaks instead of inwardly into the firebox, thereby giving an indication of the breakage 40 which is more readily observed.

A further object is to provide a staybolt having a sealed or steam-tight connection between the same and the adjacent sheet, at the same time permitting the desired flexi- 45 bility between the two.

Other objects and advantages will be apparent from the following description directed to three embodiments of the invention, which are illustrated in the accompanying 50 drawings.

Figure 1 is a section through the outer and inner sheets, showing the staybolt in side elevation, one end of the staybolt having a cap providing a flexible but tight connection at that end only;

Fig. 2 is a similar view of a staybolt provided with a flexible sleeve;

Fig. 3 is a similar view of a staybolt with means providing a flexible connection with these sheets at each end.

The staybolt 10 shown in Fig. 1 may be of any suitable outline, being provided with an enlarged head 11, preferably spherical in part, which cooperates with a correspondingly shaped seat formed in the opening 12 in the outer sheet 13, through which said staybolt passes. The head and the seat form a ball and socket joint, permitting movement of said staybolt through a considerable angle with reference to the plane of said sheet. The other end of said staybolt in this case is shown in the conventional form heretofore used, having a screw-threaded portion 14 passing through a screw-threaded opening in the inner sheet 15, the projecting end of said staybolt being upset to form a head 16, thereby forming a substantially steam-tight joint and practically a rigid connection between said staybolt and said sheet. The outer end of said staybolt 75 is provided with an opening 17 extending at least as far as the point where staybolts usually break, said breakage ordinarily occurring near the outer end thereof. Said opening may extend, however, nearly to the end of said bolt, or throughout the entire length thereof.

The outer end of the opening 17 is enlarged to form a recess 18 which is preferably non-circular whereby a tool may be inserted and used to rotate the staybolt to screw the inner end thereof through the inner sheet when the staybolt is first put in place.

To prevent the escape of steam by leakage 95 through the ball and socket joint, the outer end thereof is secured by a suitable cap or housing which in the present instance is shown in the form of an annular channel member 19 preferably stamped or pressed 100 from sheet metal and having its outer flange abutting against the outer wall of the outer sheet 13, the inner flange thereof abutting against the outer surface of the staybolt. Said outer flange is preferably 105 welded to said sheet 13 as shown at 20, and the inner flange is welded to the staybolt head as shown at 21, this welding being preferably autogenous welding, being readily accomplished by means of an elec- 110

tric arc struck between the work and a metallic electrode held in the hand of the operator. These welded joints are steam-tight, the metal of the respective parts being integrally united. The outer surface of the annular cap 19 is preferably corrugated in section to increase its flexibility, whereby the slight angular movement of the staybolt 10 with reference to the outer sheet 13 will be readily taken up without danger to the welded joints. Said cap being annular in this case provides a central opening in communication with the opening 17 in the staybolt, whereby if the staybolt 10 should break near the outer end thereof, steam will blow out through the opening 17 and through the central opening in the cap, and leaking through the magnesia lagging or insulating covering on the outside of the boiler wall (not shown) will give a clear indication of the leak, which may be readily located by removing some of said lagging. In renewing the staybolt, the cap 19 may be readily chipped off, the broken pieces of the staybolt removed, a new staybolt substituted, and a new cap welded in place.

In Figure 2 the staybolt 10 may be assumed to be similar to that shown in Figure 1, with or without the central opening. The ball and socket joint in this instance is formed by the head 11 and a sleeve 22, the opening 23 through which said sleeve passes being larger than in the first instance. Said opening is preferably tapered and receives the correspondingly tapered or conical outer end of said sleeve, the outer edge of which is welded to the outer wall at 24. The outer surface of said sleeve may be made flush with the outer surface of the sheet 13 if desired. The inner end of said sleeve is preferably corrugated or otherwise formed to make it more flexible and is welded to the shank of the staybolt at 25. The diameter of the corrugated portions is less than the minimum diameter of the opening 23, whereby said sleeve may be welded to said staybolt before being passed through said opening. The inner end of said staybolt is screwed into the opening 15 in the inner sheet 13 before the sleeve is welded to the outer sheet.

The staybolt shown in Figures 1 and 2 is thus provided with a flexible steam-tight connection with the outer sheet 13. As a result, relative movement of the sheets in substantially parallel planes results in distorting the inner sheet, which is of thinner metal than the outer sheet, whereby said inner sheet tends to assume a somewhat wavy form in cross section, although the actual distortion is of course very slight. Stresses are set up, however, which tend to rupture said sheet, and stresses are also set up in the staybolts which tend to break the same, and considerable difficulty with

such breakage is encountered in practice. Furthermore, the upsetting or heading of the inner end 16 of said staybolts tends to crystallize the metal if ordinary mild steel is used, as a result of which it is necessary to make the staybolts of a more expensive, high-grade iron.

To overcome these defects, I have shown in Figure 3 a staybolt which has a flexible connection with the boiler walls at each end thereof. As a result of this arrangement, bending stresses in the staybolt are practically eliminated, and I am therefore enabled to use a staybolt of ordinary mild steel or similar metal and also to reduce the diameter of the staybolt, thus effecting a substantial economy. Said staybolt 26 is provided with an enlarged head 27, which in this case is shown as forming a flexible connection at the inner sheet instead of at the outer sheet. Said head engages a sleeve 28 substantially the same as that previously described, said sleeve being welded at 29 to said inner sheet and at 30 to said staybolt shank. Said staybolt may be of hollow construction under certain conditions, the opening 31 therein communicating with the fire box in this instance instead of with the outer air. The opposite end of said staybolt is screw threaded at 32 and carries a nut 33 having a spherical zone which fits in a seat in a sleeve 34, the latter being screw threaded into an opening in the outer sheet. Said sleeve is provided with a removable screw-threaded cap 35 providing a steam-tight connection.

It will be seen that a ball and socket joint is provided at each end of the staybolt whereby perfect freedom of movement of the outer and inner sheets in parallel planes is permitted, said sheets being held against separation by the said staybolt. If said staybolt breaks, steam blows into the fire box and may be observed when the latter is inspected at the end of a run. However, with the flexible connections as described, there is much less likelihood of breakage. It will be noted that this form of staybolt may be assembled without hammering, whereby initial crystallization is avoided. It is necessary to assemble the staybolt from within the firebox, as experience shows that it is not desirable or practical to have the end of the staybolt or adjuncts, such as sleeves, caps, etc., projecting inwardly beyond the firebox wall 15. For this reason it is desirable to have the inner end of the staybolt substantially flush with the firebox wall as in Figures 1 and 2, the same desirable result being obtained in Figure 3 also, in which a flexible steam-tight connection is provided. There is less objection to a projecting sleeve or cap at the outer end of the staybolt as there is no danger of said projection burning off as would happen if it

were at the inner end of said bolt. The ball and socket arrangement provided at the outer end of the staybolt shown in Figure 3 is simply a conventional device.

5 It is to be understood, however, that a welded sleeve may be used in this case also, either in the form shown in Figures 1 and 2 or in various other forms. In fact, various changes and modifications may be
10 made in the forms of invention described herein, which forms are selected for the purpose of illustration only, and are not intended to exclude such other modifications as fall within the scope of the appended
15 claims.

What I claim is:

1. The combination with the outer and inner sheets of a boiler having aligned openings therein, of a staybolt passing through
20 said openings, and having an enlarged head at its inner end, said head having a spherical zone cooperating with a correspondingly shaped seat to provide a ball and socket joint, the end of said staybolt being substantially flush with the inner surface of said inner sheet, the opposite end of said bolt being provided with a member having also a spherical zone cooperating with a corresponding seat to form a second ball and
30 socket joint whereby angular movement of each of said sheets with reference to the staybolt is permitted.

2. In a staybolt construction, the combination with a boiler wall having an opening
35 therein, of a staybolt passing through said opening having an enlarged head, a circular member arranged concentric with the axis of said staybolt and having a flexible portion, said member being welded at one edge to said boiler wall and at another edge to said staybolt, said welded portions forming complete circles and providing steam-tight connections.

3. The combination with a boiler wall
40 having an opening therein, of a staybolt having a diameter less than that of said

opening and passing therethrough, an enlarged head for said staybolt, and a sleeve fitting said opening and arranged between said head and said wall, the outer end of said sleeve being welded to said wall and the inner end thereof being welded to said staybolt, said sleeve having a corrugated portion surrounding the shank of said staybolt and of a diameter less than that of said
50 opening to permit assembly.

4. The combination with a boiler wall having a tapering opening therein, of a metallic sleeve having a tapering end fitting
55 said opening, a staybolt passing through said sleeve and having a spherical head fitting a corresponding seat in said sleeve to provide a ball and socket joint, a portion of said sleeve surrounding the shank of said staybolt and being corrugated to render the same more flexible, one part of said sleeve being welded to said staybolt shank, and another part thereof being welded to said wall to provide a flexible steam-tight connection.

5. In a staybolt construction, the combination with a boiler wall of a staybolt having a rounded end portion, means providing a seat for said end portion to form a flexible joint, thereby permitting angular movement
70 of said bolt with respect to said wall, and a third member integrally united to said movable staybolt and to the adjacent portion of the stationary structure.

6. The combination with a boiler wall having an opening therein, of a staybolt having a diameter less than that of said opening and passing therethrough, an enlarged head for said staybolt, and a sleeve fitting said opening and arranged between said head and said wall, the outer end of said sleeve being secured to said wall and the inner end thereof being secured to said staybolt to form a steam-tight joint.

In testimony whereof, I have subscribed my name.

ROBERT S. MENNIE.
